UNITED STATES PATENT OFFICE.

GEORGE SIMCOE, OF TRENTON, NEW JERSEY.

TUBULAR INSULATOR.

1,072,999.

Specification of Letters Patent. Patented Sept. 9, 1913.

Application filed October 1, 1912. Serial No. 723,278.

To all whom it may concern:

Be it known that I, GEORGE SIMCOE, a citizen of the United States, and a resident of Trenton, in the county of Mercer and State of New Jersey, have invented a new and Improved Tubular Insulator, of which the following is a full, clear, and exact description.

This invention relates to insulators or circuit breakers and has particular reference to devices of this character employed for the purpose of supporting electrical conductors, guy wires, or in other capacities where it is desired to prevent the transmission of electric currents.

Among the objects of the invention is to construct an insulator of the character referred to which may be easily and cheaply manufactured by the use of any suitable machines and which devices will not only be structurally strong, but will be of superior design with respect to electrical conditions.

The foregoing and other objects of this invention will hereinafter be more fully described and claimed and illustrated in the drawings accompanying this specification in which like characters of reference indicate corresponding parts in all the views, and in which—

Figure 1 is a vertical section of one type or design of my improved insulator; Fig. 2 is a similar view of the same taken at right angles to Fig. 1; and Figs. 3 and 4 are views corresponding to Figs. 1 and 2 respectively of another form.

Referring particularly to the drawings I show at 10 the main portion of my insulator which is made preferably in or by a standard tube machine, using plastic clay as the material. I prefer this material especially for high tension service, although for certain purposes as, for instance, in low voltage, dust may be used.

As shown in Figs. 1 and 2, the insulator 45 is provided with a pair of holes 11 and 12 extending longitudinally therethrough parallel to each other, said holes being connected by a transverse channel 13 at one end of the insulator. The bottom of this chan-

nel 13 is preferably bounded so as to provide an easy curvature for an attaching device in the form of cable or wire 14 extending through the holes 11 and 12. I also provide a transverse hole 15 extending through the insulator at substantially the center thereof and at the center of curvature of said channel bottom. This transverse hole is for the purpose of another attachment indicated at 16. At 17 I provide lateral extensions or skirts preferably on both sides of the insulator adjacent the one end thereof which may be made integral with the insulator or separate therefrom and suitably connected thereto. The insulator as shown in these figures being substantially flat, the skirts 17 provide sufficient spacing of the attachment 16 from the attachment 14. The cable 16 may be seated in notches 17' to assist in maintaining the parts in proper relation to one another.

In Figs. 3 and 4 the insulator body 10' is of a slightly different form from that shown in Figs. 1 and 2, but is provided with corresponding longitudinal parallel holes 11' and 12' connected by a transverse depression or seat 13'. I also provide a single transverse hole 15' having similar characteristics to those described in connection with the first form of the invention. As indicated in Fig. 4, one end of the insulator is flared outwardly at 17' corresponding to the skirts 17 above described. As a means to increase the surface area of these insulator bodies they may be formed with corrugations 18 and either end may be provided with a circumferential groove 19 for the same purpose. These corrugations and grooves also assist in excluding ice and dirt.

Having thus described my invention, I so claim as new and desire to secure by Letters Patent:—

In a device of the character set forth, an insulator body of tubular formation having a pair of holes extending therethrough longitudinally and having an opening arranged at a right angle to the aforesaid holes, and connectors disposed respectively

in said holes and said opening and extending from the body in opposite directions, said body being formed adjacent one end with a plurality of corrugations and at the other end with a circumferential groove 24, substantially as set forth.

In testimony whereof I have signed my

name to this specification in the presence of two subscribing witnesses.

GEORGE SIMCOE.
